WALL OF PRE-CAST SLABS

Dale R. Anderson, Minneapolis, Minn.

Application August 23, 1955, Serial No. 530,060

1 Claim. (Cl. 72—107)

My invention relates generally to wall structures, and more particularly to walls made from cementitious material, and pre-cast monolithic slabs therefor.

An important object of my invention is the provision of relatively large pre-cast slabs of concrete or the like, and of novel means whereby said slabs may be locked together in side-by-side relationship to provide a wall structure which is quickly and easily assembled, and which possesses great strength and durability.

Another important object of my invention is the provision of novel means for sealing the joints between the pre-cast slabs of my invention and for locking the same together to provide a relatively smooth continuous wall surface.

Another object of my invention is the provision of a pre-cast wall-forming slab of the above type having novel means whereby adjacent ones of said slabs may be properly positioned with respect to others thereof when the supporting surface therefor is rough and uneven.

A still further object of my invention is the provision of releasable locking means for temporarily anchoring adjacent slabs together during assembly of my novel wall structure.

The above and still further highly important objects and advantages of my invention will become apparent from the following detailed specification, appended claims and attached drawings.

Referring to the drawings, which illustrate the invention, and in which like characters indicate like parts throughout the several views:

Fig. 1 is a fragmentary view in plan of a wall structure built in accordance with my invention;

Fig. 2 is a view in front elevation of the structure of Fig. 1;

Fig. 3 is an enlarged fragmentary detail corresponding to a portion of Fig. 2, some parts being broken away and some parts shown in section;

Fig. 4 is a fragmentary horizontal section taken substantially on the line 4—4 of Fig. 3;

Fig. 5 is an enlarged fragmentary vertical section taken on the line 5—5 of Fig. 2; and

Fig. 6 is an enlarged fragmentary section taken on the line 6—6 of Fig. 2.

Referring with greater detail to the drawings, the numeral 1 indicates a generally flat wall comprising a plurality of like wall sections in the nature of relatively large monolithic slabs 2 that are mounted in side-by-side relationship on an elongated base member or footing 3. The footing 3 is, like the slabs 2, preferably made from concrete or like cementitious material and rests upon the ground, indicated at X, see Fig. 2. Also preferably and as shown, the footing 3 is provided with an elongated upper surface 4 upon which the slabs 2 are adapted to rest.

Each of the slabs 2 is generally rectangular in form, having front and rear wall surface elements 5 and 6 respectively; parallel side wall surfaces 7 and parallel top

2

and bottom wall surfaces 8 and 9 respectively. The bottom wall surface 9 of each slab 2 comprises a pair of longitudinally spaced flat surface portions 10, one each adjacent the lower end of each of the side wall surfaces 7, 5 and longitudinally extended angularly disposed portions 11 between the flat surface portions 10, said angularly disposed portions 11 converging toward the bottom of the slab, see Fig. 6. The converging bottom surface portions 11 cooperate with the top surface 4 of the footing 3 10 to provide inwardly tapering recesses 12 which are adapted to receive wedges not shown, for the purpose of truing up the slabs 2 in the event of roughness or unevenness of the supporting surface 4. For the purpose of placing the slabs 2 in a straight line, so as to achieve a wall structure 15 that is straight and even, I provide stop elements in the nature of locating pins or the like 13 which project upwardly from the top wall surface 4 of the footing 3, and against which portions of the front wall surface element 5 of each slab abut.

20 The opposite side wall surfaces 7 of each of the pre-cast slabs 2 of my invention define a laterally outwardly opening channel 14 which preferably extend from the top wall surface 8 to the bottom wall surface 9 thereof. A plurality of horizontally disposed vertically spaced 25 generally U-shaped anchoring loops 15 extend horizontally outwardly from the bottom of the channel 14 at one side of the slab 2, and a plurality of like anchoring loops 16 extend horizontally outwardly from the bottom of the channel 14 at the opposite side of each slab 2 in vertically 30 offset relationship to the anchoring loops 15. As shown in Fig. 4, the imbedded inner ends of the anchoring loops 15 and 16 toe inwardly toward each other as indicated at 35 17 to prevent the anchoring loops 15 and 16 from being accidentally pulled outwardly from the slabs 2. When a plurality of slabs 2 are placed on the footing 3 in side-by-side relationship with their side wall surfaces 7 in abutting relationship, the adjacent channels 14 cooperate to form cavities 18 which extend vertically for the full height of the slabs 2. With the slabs 2 thus positioned, the 40 looped outer ends of the anchoring loops 15 and 16 cooperate to define vertically extended passageways 19 within the cavities 18. The passageways 19 are each adapted to receive a reinforcing rod 20, each of said reinforcing rods being provided with a plurality of spider-like centering elements 21 which engage adjacent looped outer ends of the anchoring loops 15 and 16 to center the reinforcing rods 20 in their respective passageways 19. It will be appreciated that the anchoring loops 15 and 16 45 as well as the reinforcing rods 20 are preferably made of ferrous metal such as steel or the like commonly used in reinforced concrete structures.

When a plurality of slabs 2 have been placed on the footing 3 with their adjacent side walls 7 in abutting relationship, and with the reinforcing rods 20 placed in the 50 passageways 19 defined by the anchoring loops 15 and 16, the cavities 18 and their passageways 19 are preferably filled with suitable cementitious material such as concrete in a plastic condition. Thereafter, when the concrete material within the cavities 18 and passageways 19 has set 55 or hardened, the entire wall structure 1 results in an integral mass of great rigidity and strength, particularly adapted for basement or foundation walls and capable of supporting relatively heavy building structure thereon.

For the purpose of temporarily holding adjacent slabs 60 2 together until the same are cemented by the concrete filling the cavities 18, I provide anchoring bars 22, one of which is shown, see Figs. 1 and 2. The anchoring bars 22 are preferably made from structural angle iron or the like and are positioned so as to extend generally horizontally across the joint between adjacent slabs 2, said joint being defined by abutting side wall surfaces 7. With reference to Figs. 1 and 2, it will be seen that the slabs 2 are 65

provided with openings 23 extending transversely therethrough, said openings 23 being adapted to receive nut-equipped bolts 24 that extend through suitable apertures in the anchoring bars 22. It will be noted that the anchoring bars 22 are positioned near the top walls 8 of the slabs 2 and serve to firmly anchor adjacent slabs together and in alignment with each other during assembly of the wall structure and until the concrete within the cavities 18 has hardened, after which time the bolts 24 and anchoring bars 22 may be removed and the transversely extending holes 23 filled with cement if desired. With reference to Figs. 2 and 6, it will be seen that the top surface 4 of the footing 3 forms the bottom of a longitudinally extending upwardly opening channel 25, which is preferably filled with concrete during subsequent building operations such as, for instance, the pouring of a concrete floor or the like.

The top surfaces 8 of the several slabs 2 are provided with aligned longitudinally extending upwardly opening channels 26 for the reception of suitable building parts not shown but which are adapted to rest therein. For facilitating handling of the slabs 2 I provide a pair of longitudinally spaced upwardly opening recesses 27 in the top wall 8 of each of the slabs 2, and a pair of inverted generally U-shaped members 28 imbedded in the upper end portion of each slab 2. The looped upper ends 29 of each member 28 extends upwardly from the bottom of its respective recess 27, and is adapted to be engaged by the lifting hook of a crane or the like, not shown. With reference to Fig. 5, it will be seen that the lower ends of the U-shaped members 28 are toed inwardly toward each other, as at 30, to prevent accidental removal of the members 28 from their respective slabs 2.

While the pre-cast slabs 2 may be produced in various sizes, I prefer to produce the same substantially equal in height to that of a normal basement when the wall 1 is to be used as a basement wall. The slabs 2 are equally adapted for use as outside walls of a basement or building as well as for inner walls or partitions thereof. Also, if desired, the slabs 2 may be formed with cut-out portions, shown by dotted lines in Fig. 2 and indicated at 31, to form window openings. Obviously, the same may be provided with pre-cast door openings where desired.

I have found that much time and expense has been saved in the building of a wall structure utilizing the pre-cast slabs of my invention, and that the relatively few joints in such a wall structure contribute to an extremely strong and rigid building foundation.

While I have shown and described a commercial embodiment of my novel wall structure and pre-cast slab therefor, it will be understood that the same is capable of modification without departure from the spirit and scope of the invention as defined in the claims.

What I claim is:

A wall including a plurality of pre-cast slabs each comprising a generally rectangular monolithic body having front and rear wall surfaces, parallel top and bottom wall surfaces and vertical sides each comprising spaced co-planar vertical side wall surfaces defining therebetween a laterally outwardly opening channel extending downwardly from said top wall surface, said slabs being vertically disposed in side by side relation with the adjacent side wall surfaces thereof in abutting engagement, adjacent ones of said channels cooperating to provide a vertically disposed cavity between the abutting slabs, a plurality of horizontally disposed semi-circular anchoring loops projecting laterally outwardly from the bottoms of said channels into said cavity, the loops of one channel overlapping the loops of the adjacent channel with each loop of the one channel providing with the adjacent loop of the adjacent channel a pair of loops defining a vertical opening substantially circular in cross section, the openings of the pairs of loops being registered vertically to define a passageway substantially concentric to said cavity, and a reinforcing bar extending vertically through said passageway, said reinforcing bar having axially spaced therealong groups of circumferentially spaced axially extending centering elements projecting radially outwardly from said bar, said centering elements engaging circumferentially spaced portions of the pairs of said loops and aligning the reinforcing bar on the axis of said passageway, said cavity being adapted to be filled with cementitious material to seal the adjacent slabs together.
